US00D568313S

(12) **United States Design Patent** (10) Patent No.: **US D568,313 S**
(45) Date of Patent: **** May 6, 2008**

(54) **USB MEMORY WITH LASER POINTER AND REMOTE CONTROL**

(75) Inventor: **Chun Fai Leung**, Kowloon (HK)

(73) Assignee: **P.S.L. Limited**, Kowloon (HK)

(**) Term: **14 Years**

(21) Appl. No.: **29/278,850**

(22) Filed: **Apr. 12, 2007**

(51) **LOC (8) Cl. 14-02**

(52) **U.S. Cl. D14/356; D26/38**

(58) **Field of Classification Search D14/436,**

(57) **CLAIM**

The ornamental design for a USB memory with laser pointer and remote control, as shown.

DESCRIPTION

FIG. 1 is a front elevational view of a USB memory with laser pointer and remote control showing my new design; FIG. 2 is a rear elevational view thereof;

FIG. 3 is a top plan view thereof;

FIG. 4 is a bottom plan view thereof;

FIG. 5 is a right side view thereof;

FIG. 6 is a left side view thereof;

FIG. 7 is a perspective view thereof; and,

FIG. 8 is a perspective view thereof with the USB detached.
